(Cl. D14—3)

Fig. 1

Fig. 2

Fig. 1 is a rear perspective view of a tractor, showing my new design; and

Fig. 2 is a front perspective view thereof.

The side of the tractor opposite to the side shown in the drawings is substantially a duplicate of the side shown.

The dominant features of my design reside in the portions shown in full lines.

I claim:

The ornamental design for a tractor, substantially as shown and described.
